DESIGN FOR A WRIST WATCH STRAP OR
SIMILAR ARTICLE

Charles B. Greenberg, New York, N. Y.

Application August 14, 1946, Serial No. 132,513

Term of patent 7 years

(Cl. D45—4)

To all whom it may concern:

Be it known that I, Charles B. Greenberg, a citizen of the United States, residing in the city, county, and State of New York, have invented a new, original, and ornamental Design for a Wrist Watch Strap or Similar Article, of which the following is a specification, reference being had to the accompanying drawing, forming part thereof.

Fig. 1 is a plan view of a wrist watch strap or similar article, showing my new design;

Fig. 2 is a side elevational view thereof and

Fig. 3 is a perspective view of the same.

The essential features of my design reside in the configurations of the buckle and the keepers.

I claim:

The ornamental design for a wrist watch strap

or similar article, substantially as shown and described.

CHARLES B. GREENBERG.
